SWITCH STRUCTURE

Charles J. Breitenstein, Chicago, Ill., assignor to
Raymond T. Moloney, Chicago, Ill.

Application October 24, 1936, Serial No. 107,468

8 Claims. (Cl. 200—8)

The invention relates to motor driven members such as a check or coin handling apparatus, and particularly to a switch structure therefor to determine the period of operation of the motor, 5 and as a consequence the number of checks dispensed.

Dispensing apparatus of the type referred to is useful in many organizations and usually comprises a unit embodying a base plate carrying an 10 upright tube or magazine loaded with the coins or checks to be handled or dispensed. Operatively associated with the lower end of the magazine is an ejector member preferably in the form of a slide to receive and dispense checks from 15 the magazine on each operative stroke thereof. This slide is driven by an electric motor device, such as a motor or equivalent, and the ejector will operate to make passes relative to the magazine so long as the motor remains energized. To 20 limit the time of operation of the motor and thus to control the number of passes and checks dispensed by the ejector it has been proposed to provide various forms of electric control switches and timers operable from the ejector. In the 25 past, depending upon the organization with which the check handling apparatus was to be used, it was found necessary to provide different forms of timer switches to govern the apparatus in accordance with particular situations and 30 results sought. In other words no universal timer was available to meet all situations involving varying the number of dispenser operations to be performed.

With this general situation in mind the main 35 object of the present invention is to provide an improved switch structure for a motor driven check handling apparatus or the like.

Another object of the invention is to provide such means in the form of a rotary timer switch, 40 embodying means affording a maximum number of adjustments to vary, as desired, the periods of operation of the motor.

Still another object of the invention is to provide a timer of simple form adapted for universal 45 use with all check handling mechanisms of the type mentioned so as to eliminate the necessity for providing different timers for every situation of use of such check handling mechanisms.

Another object is to provide such control means 50 which will be cheap to produce and positive in operation.

Other important objects of the invention will become apparent to those skilled in this art as the disclosure is more fully made.

Briefly, these important objects may be

achieved by the illustrative example of the invention herein disclosed, wherein the switch structure comprises a stationary contact and brush carrying plate adjacent a rotatable conductor plate with which the brushes are in electrical contact. The rotary plate is driven in a step by step manner from the movement of the motor driven ejector and the operation of the motor continues until an insulator portion on the rotary plate breaks the circuit through a brush, 10 whereupon the motor and the dispensing action ceases. Thereafter, the rotary plate may be reset to its initial starting position for repeat operations as desired. By varying the positions of the brushes any number of combinations as desired, 15 within limits, may be achieved to vary the time of operation of the motor.

So much will suffice in presenting a general view of the novel structure, which in one practicable form is shown in the accompanying drawings, wherein:

Figure 1 is a general plan view of a check handling apparatus with which is operatively associated the improved control, or timer means of this invention;

Figure 2 is a general side elevational view of the complete unit.

Figure 3 is a transverse cross sectional view through the control mechanism taken along the line 3—3 of Figure 2, looking in the direction of 30 the arrows;

Figure 4 is a detail face view of the stationary switch plate per se, taken from the line 4—4 of Figure 1, looking in the indicated direction; and,

Figure 5 is a cross sectional view to show the 35 rotary conductor plate of the timer, taken along the line 5—5 of Figure 1, looking in the direction of the arrows.

In Figure 1, a reset solenoid, later to be described, has been left off to make the under structure more clear.

The check handling apparatus illustrated may be of any standard form, and herein for the sake of illustration, it comprises a unit, including a horizontal base plate 10, along one side of which is mounted a smaller horizontal plate 11 held in spaced relationship to the base plate by four screw posts 12, including spacers 13. Said plate 11 is formed with a circular opening and in registration therewith said plate 11 carries an 45 standing tube 14 forming a magazine containing the checks or coins to be handled and dispensed.

Slidably operable over the base 10 between the pairs of posts 12 is an ejector, herein shown by way of example, as a reciprocatory slide 15 hav-

ing an opening 16 therein to receive checks by gravitation from the tube 14 when said opening 16 is in registration with the tube. The base 10 is formed with a check drop opening 17 below 5 the slide 15 in an offset position from the lower end of the tube in the usual manner.

When the slide 15 is in check receiving position relative to the magazine it is in its normal position with one end thereof abutted against a pair 10 of upturned end stops 18 formed at one edge of the base plate 10. At the opposite end of the slide 15 is a screw post 19 around which is hooked a spring 20, the other end of said spring being secured to a tang 21 formed on the stationary 15 top plate 11. Thus, the spring 20, in a manner later to appear, serves to pull the slide 15 to its normal position abutting the end stops 18. The screw 19 is a set screw but does not screw down 20 into the slide 15 but merely rests loosely thereon.

Adjacent the screw post 19 the side of the slide 15 is notched as at 22 to provide rigid upstanding integral bracket or arm 23 for a purpose soon to appear.

To one side of the top plate 11 the base plate 10 carries another plate 24 serving as a bracket for mounting an electric motor 25, or equivalent power device such for example as an electromagnet. This motor has a shaft 26 carrying 30 fast thereon a worm gear 27 in mesh with and driving a reducer worm wheel 28, said latter wheel being fast on a transverse shaft 29 journaled in suitable brackets 30, as shown. This shaft 29 extends a substantial distance as shown 35 in Figure 1 to a point above the slide 15 where it carries and turns a blank wheel or disk 31 on which is mounted an eccentric pin or roller 32 turning with the wheel in a vertical plane where it can engage the bracket arm 23, heretofore 40 described.

The screw 19 is threaded into and through a horizontal angular extension 33 of a pivoted pawl 34. Said pawl is pivotally mounted intermediate its ends by means of a pivot pin 35 carried in an upstanding arm 36 included in the extreme left hand end of the slide 15 as viewed in Figures 1 and 2. By means of a lock nut 37 and by turning the screw 19 the extension 33 may be raised or lowered in relation to the slide 15 50 whereby the operative end of said pawl 34 may be properly positioned in relation to a ratchet wheel presently to be described. It can now be seen that the pull of the spring 20 is through the screw 19, pawl 34 and post 36 for holding the 55 slide 15 normally against the end stops 18. The line of pull of said spring 20 also is such as to hold the lower end of the screw 19 loosely abutting the top side of the slide 15. This brings the control means for the motor 25 next in line for 60 description and accordingly attention is directed to Figures 1 and 3.

A plate 38, in channel form, is secured by screws 39 to the base plate 10 off the driving end 65 of the motor 25, said plate thus providing two parallel, spaced, upstanding walls 40 and 41. A spacer sleeve 42 is turnably mounted in the wall 40 for rotation about a horizontal axis provided by a transverse shaft 43 passing through said sleeve 42. By means of a pin 44 the shaft and 70 sleeve turn together. The sleeve projects through the wall 40 as shown in Figure 3 where it has a reduced end to which is firmly secured a ratchet wheel 45 positioned to be engaged by the pawl 34, heretofore described.

75 The wall 40 carries a bolt 46 radially out-

wardly of the periphery of the wheel 45 as shown in Figure 2, on which bolt is pivotally mounted a dog 47 having a bent end 48 to engage the teeth of the ratchet wheel. Said dog, by means of a coil spring 49 wound around the bolt 46 and a leg engaging the lever or dog 47 is held normally to duty in the wheel teeth as seen in Figure 2. The dog lever 47 above its fulcrum carries a pin 50 embraced by a notch 51 in an armature 52 for a so-called reset solenoid 53 mounted by means of a bracket 54 on the upper end of the wall 40, as shown. The solenoid 53 is included in any suitable circuit with a source of energy as indicated at 55, said circuit being normally broken by means of a normally open switch 56 so that the solenoid under normal conditions remains deenergized.

The stationary wall 40 has hooked into an opening therein one leg of a spring 57 coiled around the sleeve 42 between the wall 40 and 20 ratchet wheel, while the other leg of said spring is secured to a pin 58 carried by the ratchet wheel 45, as shown. As the wheel 45 turns in a clockwise direction as viewed in Figure 2 it can be seen that the spring 57 is wound and stores 25 energy which cannot be released to drive the ratchet wheel back to its initial starting position until the dog 47 is released. To insure where this initial starting position will be the wall 40 rigidly carries a stop block 59 and the ratchet wheel 45 30 near its periphery carries a stop pin 60. In other words, the wheel 45 can be driven reversely by the spring 57 until its pin 60 abuts the stop block 59.

The shaft 43 at its opposite end, by means of 35 a pin 61 has fixed to it to turn therewith a sleeve 62 turnable also in the stationary wall 41. The end of the sleeve 62 adjacent the sleeve 42 has fitted thereon to turn therewith a disk 63 which has riveted thereto a larger but insulated disk 40 ring 64. Said ring 64 in turn has riveted to it a still larger but conductor ring 65 and a segment 45 of the periphery of said latter ring carries an insulator strip 66 of the desired arcuate length, said strip 66 as shown in Figure 5 throughout its length projecting radially outwardly beyond the outer periphery of the ring 65. This result is brought about by cutting away as at 66' a portion of the periphery of the wheel 65 equal to the length of the segment 66. Thus the periphery 50 of the disk wheel 65 is concentric and formed by a portion of the disk 65 and the remainder of said periphery is formed by the strip 66.

By means of rivets 67 there is rigidly secured to the wall 41 a circular non-conductor or insulated disk 68 through which the sleeve 62 also is passed as seen in Figure 3. Secured to the disk 68 is a flat spring wire brush 69 bearing against the conductor ring 65 as shown in Figure 3. This brush 69 by means of a wire 70 is in connection 60 electrically with the motor 25.

A segment of the disk 68 is provided along radial lines and in equidistantly spaced angular relationship with pairs of holes 71 any pair of which is adapted to have secured therein by 65 screws 72 an angle bracket 73 carrying a conductor brush 74 the free end of which is V-shaped in cross section and rests on the periphery of the conductor disk 65. Thus, these brushes span and space between the two disks 68 70 and 65 as shown in Figure 1. One brush 74, shown in Figure 1, is connected by a wire 75 with a source of energy 76 and a wire 77 to the motor 25. In the wire 77 is disposed a normally open switch 78. It can be seen now that with the 75

brush 69 and wire 70, disk 65, motor 25, a brush 73, wire 75 and battery 76 in circuit, that the motor 25 will be energized and operates when the key switch 78 is closed.

5 Similarly each of the brushes 73 can be wired in a circuit with the source of energy and the motor with separate switches 78 in each said circuit, so that any one of a number of switches 78 can be successively closed to cause operation 10 of the motor and check handling apparatus. The use and operation of the structure will now be described.

In Figures 1 and 2 all parts are shown in their starting position preparatory to the making of 15 a controlled dispenser operation. A switch 78 for a brush 74 and the motor 25 is opened so that the latter stands deenergized. Of course, the solenoid 53 in another circuit also stands deenergized and consequently the dog 48 engages 20 the teeth on the ratchet wheel 45, the latter also by means of the stops 59, 60 being in an initial starting position. The pawl 34 carried on the slide ejector 15 is withdrawn from the ratchet wheel because the spring 20 has the slide pulled 25 back against the stops 18. This means that the opening 16 in the slide is in check receiving position relative to the tube 14.

Only one circuit 75 for a brush 74 is shown and we will assume this is for the first and lowermost 30 brush 74 shown in Figure 5 where an arrow indicates that the wheel 65, as viewed, turns counterclockwise with the brush 74, of course, standing stationary. When the key switch 78 is now closed a circuit is completed as heretofore 35 described to energize the motor 25.

Consequently the shaft of the motor drives the gearing 21, 28 and shaft 29, which in turn drives the wheel 31. Thus the roller 32 engages and wipes against an edge of the upright 40 bracket 23 to move the slide 15 away from its home position to dispense a check lodged in the slide through the check drop opening 17 in the base 10. The slide, as its solid part passes under the magazine, supports the column of checks 45 therein in the well known manner. The slide may if desired be twice the thickness of the checks thereby making it possible to handle two checks on each stroke of the slide. As the slide is thus moved the pawl 34 is also moved to engage the ratchet wheel 45 and move it in the direction indicated by the arrow as viewed in Figure 2. The stroke of the pawl 34 is such that the ratchet wheel is moved but one tooth distance 50 away from the stop 59 for each stroke of the slide 15. As the ratchet wheel 45 is moved in the manner indicated the spring 57 is wound and the dog 48 holds the gain of the ratchet wheel. 55

The ratchet wheel 45 carries turnable with it the disk 65 one step which is just sufficient to bring the insulator strip 66 under the first brush 74 as viewed in Figure 5 whereupon the circuit through the conductor disk 65 is broken and the motor 25 is deenergized.

By this time also, the roller 32 has moved 60 away from the bracket 23 so that the spring 20 is operative to pull the slide 15 back to check loading position against the end stops 18. The pawl 34, of course, is now also in retracted position. By closing the key switch 56 the solenoid 53 may 65 be energized to pull the dog lever 47 away from the ratchet wheel 45 so that the spring 57 is operative to drive the wheels 45, 65 back to their initial starting position as determined by the stops 59, 60.

75 The first brush 74 shown in the lowermost

position in Figure 5 thus serves to make a circuit to keep the motor in operation just long enough to make one dispenser stroke of the ejector 15. If a circuit were established through the second brush 74, looking counterclockwise in 5 Figure 5, then the motor would run long enough to cause two dispenser strokes of the slide 15. Thus, for each successive brush 74 placed on the stationary disk 68 in the holes 70 therein, there would result an additional stroke of the slide. 10 Or if only one brush 74 were to be used and it were placed a considerable angular distance, in a counterclockwise direction, as viewed in Figure 15 5, away from the leading end of the insulator strip 66; then with such circuit established the motor would run until, step by step, the insulator portion reaches the said brush 74 to break the circuit.

It can now be seen that for the disclosure shown twenty brushes 74 may be used in regularly spaced sequence, or any one of the twenty 20 may be used. Thus the nearest brush 74 to the leading end of the insulator strip 66 would result in dispensing one check, and the farthest brush 74 would result in dispensing twenty 25 checks. By using a slide thick enough to move two checks on each stroke the combinations set up could be doubled. The structure is obviously such that it will be useful in most any organization employing these dispensers and the 30 timer therefor is substantially a universal unit for all situations.

It can now be appreciated that a simple structure has been provided to achieve the desirable 35 objects of this invention.

It is the intention to cover all changes and modifications of the example of the invention shown for the sake of the disclosure which do not in material respects constitute departures from the spirit and scope of the invention as herein- 40 after claimed.

What is claimed is:

1. In a switch structure, a support, a shaft 45 carried thereby, a sleeve turnable on the shaft and carrying a movable disk including an insulator ring, a conductor ring carried by the insulator ring as part of the disk, a stationary disk of insulated material associated with the support adjacent the disk and carrying a conductor wiper always contacting the proximate face of the conductor ring of the movable disk at a point inwardly of the periphery of the said ring, one or more conductor brushes rigidly carried on the periphery of the stationary disk and spanning the space between the two disks in a manner to 50 cause said latter brush or brushes to engage the periphery of the conductor ring, and means to turn the movable disk.

2. In a switch structure, a support, a movable disk supported thereby and including an insulator portion, a conductor ring carried by the insulator portion radially outwardly thereof as part of the disk, a stationary piece of insulating material carried by the support adjacent the disk and carrying a spring conductor member 60 65 wiping the conductor ring on its proximate face at a point inwardly of the periphery of the ring, one or more conductor brushes carried by the stationary piece to engage the periphery of the ring, and means to turn the movable disk. 70

3. In a switch structure, a support, a movable disk supported thereby and including an insulator portion, a conductor ring carried by the insulator portion radially outwardly thereof as part of the disk, a stationary disk of insulating material 75

- carried by the support adjacent the movable disk and carrying in an off-center position a spring conductor member wiping the conductor ring on its proximate face at a point inwardly of the periphery of the ring, said disks being of substantially the same size, one or more conductor brushes being rigidly carried by the stationary disk in a manner to span and engage to turn the movable disk.
4. In a switch structure, a support, a movable disk supported thereby and including an insulator portion, a conductor ring carried by the insulator portion radially outwardly thereof as part of the disk, a stationary disk of insulating material carried by the support adjacent the movable disk and carrying a spring conductor member wiping the conductor ring on its proximate face, said disks being of substantially the same size, one arcuate portion of the stationary disk carrying a number of angularly spaced brushes spanning the peripheral edges of both disks, the movable disk having an arcuate portion of its periphery relieved and carrying an insulated piece to overlap said relieved portion and complete the circle of the movable disk, and means to turn the movable disk.
5. In a switch structure, a support, a movable disk supported thereby and including an insulator portion, a conductor ring carried by the insulator portion radially outwardly thereof as part of the disk, a stationary disk of insulating material carried by the support adjacent the movable disk and carrying a spring conductor member wiping the conductor ring on its proximate face, said disks being of substantially the same size, one arcuate portion of the stationary disk carrying a number of angularly spaced brushes spanning the peripheral edges of both disks, the movable disk having an arcuate portion of its periphery relieved and carrying an insulated piece to overlap said relieved portion and complete the circle of the movable disk, said brushes having their end portions which contact the movable disk periphery formed in V-section in the direction of the length of the brushes, and means to turn the movable disk.

6. In a switch structure, a unit mountable in position as such and comprising a support having spaced upright walls, a stationary disk of insulated material mounted on one wall, a shaft carried in the walls, a disk turnable about the shaft axis parallel to the stationary disk and of about the same size and including an insulated portion and an outer conductor ring, a wiper carried on the stationary disk in an off center position and engaging a face of the ring inwardly of its periphery, a brush carried on the stationary disk and engaging the periphery of the movable disk, and means to turn the latter.

7. In a switch, a support, a stationary disk of insulation material carried thereby, a turnable disk on the support having an insulated portion and an outer conductor ring, the disks being parallel and of about the same size, a wiper carried by the stationary disk to engage a face of the ring inwardly of its periphery, an angle bracket carried detachably by the stationary disk, a brush carried by the bracket parallel with the axis of turning of the turnable disk and having an end engaging the periphery of the turnable disk, means to turn the turnable disk, and an arcuate portion of the periphery of the turnable disk comprising insulation material.

8. In a switch, a support, a stationary disk of insulation material carried thereby, a turnable disk on the support having an insulated portion and an outer conductor ring, the disks being parallel and of about the same size, a wiper carried by the stationary disk to engage a face of the ring inwardly of its periphery, one or more brushes carried by the stationary disk, detachable means to mount said brush or brushes in any one of a number of different angularly spaced positions along a given arcuate portion provided on a face of the stationary disk, said brush or brushes when so mounted being disposed parallel with the axis of the turning disk and each having an end spanning and engaging the periphery of said latter disk, means to turn the turnable disk, and an arcuate portion of the periphery of the turnable disk comprising insulation material.

CHARLES J. BREITENSTEIN.

CERTIFICATE OF CORRECTION.

Patent No. 2,168,057.

August 1, 1939.

CHARLES J. BREITENSTEIN.

It is hereby certified that error appears in the printed specification of the above numbered patent requiring correction as follows: Page 4, first column, line 8, claim 3, after "engage" insert the words the peripheral edge of the ring; and means; and that the said Letters Patent should be read with this correction therein that the same may conform to the record of the case in the Patent Office.

Signed and sealed this 19th day of September, A. D. 1939.
